UNITED STATES PATENT OFFICE

135,892

DESIGN FOR A PORTFOLIO

John G. Rouner, Denver, Colo.

Application January 18, 1943, Serial No. 109,285

Term of patent 14 years

To all whom it may concern:

Be it known, that I, John G. Rouner, a citizen of the United States, residing at Denver, in the county of Denver, State of Colorado, have invented a new, original, and ornamental Design for a Portfolio, of which the following is a specification, reference being had to the accompanying drawing forming a part thereof.

Fig. 1 is a perspective view in closed position of a portfolio showing my new design;

Fig. 2 is a perspective view thereof in open position; and

Fig. 3 is an end elevational view thereof with the flap in raised position.

I claim:

The ornamental design for a portfolio, as shown.

JOHN G. ROUNER.
